SANITARY RETRACTILE RAZOR STROP

Lawrence Lynch, Los Angeles, Calif.

Application February 23, 1933, Serial No. 657,958

2 Claims. (Cl. 51—202)

This invention relates to improvements in sanitary containers.

The general object of the invention is to provide a sanitary retractile razor strop.

Another object of the invention is to provide a sanitary container for a razor strop including means to wind the strop upon itself within the container.

A further object of the invention is to provide a sanitary container for a razor strop including automatic means for retracting the strop from an extended position into the container.

Other objects and the advantages of this invention will be apparent from the following description taken in connection with the accompanying drawing wherein:

Fig. 1 is a side elevation of my improved sanitary container showing a razor strop operatively associated therewith;

Fig. 2 is a front view of the device shown in Fig. 1;

Fig. 3 is an enlarged front elevation of the device with portions broken away;

Fig. 4 is an enlarged fragmentary section taken on line 4—4 of Fig. 2; and,

Fig. 5 is an enlarged section taken on line 5—5 of Fig. 1.

Referring to the drawing by reference characters, I have indicated my improved sanitary razor strop container generally at 10. As shown the container is made of metal and comprises a front wall 12, a back wall 13, side walls 14 and a bottom 15, the top being open. The front wall 12 has a notch 16 therein adjacent the top. At the bottom of the notch 16 the material of the front wall 12 may be rolled inward upon itself as indicated at 17 Fig. 4. The container is shown as provided with a clamping device 17' which includes a thumb nut 17" for securing the container in any desired position.

The open top of the container is adapted to be closed by a metal top 18 which includes side and back flanges 19 which extend downward over the sides and back of the container. The top 18 further includes a front flange 20 which extends downward over the front wall 12 of the container to approximately in line with the bottom of the front wall notch 16. The flange 20 has a notch 21 therein which opens through the lower edge of the flange. At the top of the notch 21 the material of the flange may be rolled inward upon itself as indicated at 22.

The notch 16 in the front wall 12 and the notch 21 in the flange 20 of the top member form an aperture 23 leading to the interior of the con-

tainer. The top is adapted to be secured to the container by a bolt 24 and a nut 24'. As shown the bolt 24 is positioned in suitable apertures in the side flanges 19 of the top and in aligned apertures in the sides 14 of the container.

Mounted on the inner face of each of the sides 14 of the container I show rabbeted slide members 25 in each of which a plate member 26 is positioned. Mounted on each plate member 26 I provide an annular bearing member 27. The plates 26 and the bearings 27 include coaxial apertures 28 therein. Rotatably positioned on the bearing members 27 I provide a sleeve 29 and positioned in the sleeve between the inner ends of the bearing members 27 I provide a coiled torque spring 30 one end of which is anchored to one of the bearings 27 as at 31 and the opposite end of which is anchored to the sleeve 29 as at 32.

For retaining the bearings 27 in correct positions I provide pins 33 which are positioned in the bearing apertures 28. The pins 33 are secured to a flat spring member 34 adjacent one end thereof and the opposite ends of the spring members are secured to the sides 14 as by screws 35.

Intermediate its length the sleeve 29 includes a recess 36 in its outer surface. Mounted in the sleeve 29 and traversing the recess 36 I provide a pin 37 to which is pivotally secured within one end of a loop on a flexible metal band 38.

The opposite end of the band 38 includes spaced bearing portions 39 in which trunnions 40 of a yoke member 41 are pivotally mounted. The yoke member 41 includes a semi-circular portion 42 between the trunnion portions which has an elongated slot 43 therein. Positioned in the slot 43 I provide a connector bar 44 which includes an enlarged spherical head 45 at one end a similar head 46 at the opposite end. The bar 44 is free to rotate and slide in the slot 43 and the head 45 is adapted to work and engage the inner surface of the portion 42.

Connected to the flexible strop 38 by the bar 44 I provide a razor strop 47 which may be of any desired flexible type. Secured to one end of the strop 47 as by a loop member 48 I provide a metal link member 50. As shown the link member 50 is triangular in shape with the base portion 51 thereof engaged by the loop member 48. At the apex of the link member I provide an aperture 52 therethrough in which the bar 44 is positioned. The bar 44 is free to rotate in the aperture 52 and the head 46 of the bar is adapted to engage the inner surface of the link adjacent the apex thereof.

At the end opposite the link 50 the strop 47

includes a suitable handle portion 53 adjacent which I provide a stop member 55. The stop member 55 is made of a flexible material such as rubber and has an aperture 56 therethrough in which the strop 47 is positioned. The aperture 56 is normally of less area than the cross sectional area of the strop so that when it is positioned on the strop it tightly grips the strop on all sides thereof. The upper and lower portions of the stop member 55 may each have a leaf spring member 57 embedded therein which tend to bow towards each other and thereby retain the upper and lower surfaces of the aperture 56 in tight engagement with the strop.

15 The width of the stop member 55 is greater than the width of the aperture 23 of the container so that the stop cannot pass therethrough. The rear face of the stop member 55 is preferably beveled as at 58 so that when the strop is 20 in a retracted position the stop member 55 will wedge in the passageway and completely block the entrance into the container.

25 Adjacent the bottom of the container one of the side walls 14 thereof has an aperture 59 therein in which a drawer 60 is positioned. The drawer 60 is slideable through the aperture 59 and includes an enlarged front portion 61 which completely closes the aperture 59. On the front portion 61 I provide a gasket 59' of rubber and

30 a handle member 62. On the inner face of the front portion 61 I provide one member 63 of a ball and socket latch the other portion 64 of which is mounted on the adjacent side wall 14 of the container. The gasket 61' makes a tight seal about the drawer. In use an antiseptic material 61 of any desired type either in solution or as a solid is placed in the drawer 60. When the strop is secured to the sleeve 29, the sleeve 29 and its associated bearings and bearing plates are removed from the container and the strop is wound upon itself on the sleeve 29 and then the sleeve and its associated parts are replaced in the container. Thereafter when an operator grasps the strop handle 53 and pulls the strop 40 out of the container the unwinding of the strop rotates the sleeve 29 which in turn winds up the spring 30 thus putting a torque tension on the strop.

45 When the operator releases the strop the tension of the spring 30 rotates the sleeve 29 in the opposite direction and as the sleeve so rotates it winds the strop therearound and upon itself until the stop member 55 on the strop engages the container as shown in Fig. 4. The shape of the member 50 causes it to pass readily through the aperture 23 regardless of the angle at which the

strop is held when it is released. Thus only when the strop is in use is it exposed to the atmosphere outside of the container and at all other times it is housed in the container wherein the atmosphere is saturated with fumes from the antiseptic material contained in the drawer 60 which retains the strop in a sterile condition.

80 From the foregoing description it will be apparent that I have provided a novel sanitary retractile razor strop which is simple in construction and highly efficient in use.

85 Having thus described my invention, I claim:

1. A razor strop container comprising front, back and side walls, a cover for said container, means to secure said cover to said container, said container having an elongated aperture extending substantially the full width of the front wall, a razor strop having a width corresponding substantially to the length of said aperture and extending therethrough, there being a second aperture in one of the other walls of said container adjacent the lower end thereof, a drawer, said drawer substantially filling said second aperture and being movable into and out of said container through said second aperture, said drawer extending substantially the full width of the case and positioned below said razor strop, and releasable means to retain said drawer in position in said container.

90 2. The combination of a container and a razor strop, said container comprising front, back and side walls, a cover for said container, means to removably secure said cover to said container, the front wall of said container having an aperture, opposed slide members mounted on the inner surface of said side walls, a bearing plate mounted to move in each of said slide members, said plates each having an annular bearing member thereon, a sleeve, said sleeve being rotatably mounted on said bearings, a torque spring positioned in said sleeve, one end of said spring being anchored to one of said bearings, and the opposite end of said spring being anchored to said sleeve, each of said bearings and associated plates having a coaxial aperture therein, a pin positioned in each of said bearing apertures, said pins each being secured to a flexible member and each of said flexible members being secured to said container side walls, there being a recess in said sleeve opening through the outer surface thereof, a bar in said sleeve traversing said recess, a flexible metal strap, one end of said strap being pivotally mounted on said bar and a razor strop secured to the other end of said strop.
